UNITED STATES PATENT OFFICE

LEWIS E. BUNCH, OF PAMPA, TEXAS

COMBINED MIXING AND FLOW DEVICE

Application filed June 13, 1930. Serial No. 461,023.

This invention relates to well apparatus and has for an object the provision of a combined mixing device and flow valve, which may be positioned within a well to break up and agitate the liquid and impart a swirling motion thereto, to reduce slippage to a minimum and assist the flow of liquid through the flow pipe or tube, the invention being especially adapted for use in oil wells.

10 Another object of the invention is the provision of a device which includes a mixing chamber for mixing liquid and air, the latter being forced into the well under pressure, and for utilizing the force or pressure of air 15 to operate a mixing device or agitator, the latter serving to break up the liquid before it comes in contact with the air to provide a more perfect mixture.

Another object of the invention is the provision of an agitator which will also function to force the liquid upward, which, together with the action of the air, imparts a swirling motion to the liquid and reduces slippage to a minimum.

25 With the above and other objects in view, the invention further includes the following novel features and details of construction, to be hereinafter more fully described, illustrated in the accompanying drawings and 30 pointed out in the appended claims.

In the drawings:—

Figure 1 is a sectional view of a portion of a well with the invention applied.

Figure 2 is a section on the line 2—2 of 35 Figure 1.

Figure 3 is a detail elevation of the mixing chamber, agitator, and operating means thereof.

Figure 4 is a section on the line 4—4 of 40 Figure 1.

Referring to the drawings in detail wherein like characters of reference denote corresponding parts, the reference character 10 indicates a portion of a well casing within 45 which is positioned a hollow member 11. This member is positioned adjacent the bottom of the well and is circumferentially grooved as shown at 12 for the reception of an annular packing 13. This packing tightly 50 engages the well casing and effectually shuts

off the bottom of the well. The member 11 is made in two sections threadedly connected as shown at 14 so as to facilitate assembling.

Extending into opposite ends of the member 11 are passages 15, the outer ends of these passages being in communication with sections of the flow pipe or tube 16, the latter being threadedly connected to the member 10 as shown at 17. A short pipe section or casing 18 connects the passages 15, so that a passage is provided between the flow tube sections through said member.

As stated, the member 11 is hollow and as the pipe section 18 extends through this hollow portion, an annular air chamber 19 is provided. Openings for passages 20 extend through the upper portion of the member 11 into the chamber 19.

Air is forced into the well under pressure and enters the chamber 19 through the passages 20, and from this chamber, the air is directed into a chamber 21 provided within the pipe section 18 and the adjacent passage 15, the chamber 21 providing a mixing chamber.

The air entering the mixing chamber is given a swirling action through the medium of air nozzles 22, whose outer ends communicate with the chamber 19 and whose inner ends are relatively offset as shown in Figure 4 of the drawings. Mounted in suitable bearings provided in the mixing chamber is a vertically disposed shaft 23. This shaft carries at its lower end an agitator 24 which is shown in the form of a propeller. The upper end of the shaft 23 is geared to a shaft 25, through the medium of gears 26, and this last mentioned shaft extends through the pipe 18 and has mounted upon its outer ends propellers 27.

Air entering the chamber 19 will be forced into the chamber 21 as previously stated, and as the propellers 27 are located in the chamber 19 in the path of the air, the propellers will operate to rotate the shaft 25. The shaft 23 will then be rotated through the medium of the gears 26 so as to operate the agitator 24. The oil or the liquid passing through the flow tube 16 will be thoroughly broken up before it reaches the air expelled from the nozzles 22, so that this liquid and the air will

be more thoroughly mixed. The mixture of liquid and air will pass up through the flow tube with a swirling action and slippage will thus be reduced to a minimum.

5 The invention is susceptible of various changes in its form, proportions and minor details of construction and the right is here-
in reserved to make such changes as properly fall within the scope of the appended claims.

10 Having described the invention what is claimed is:—

15 1. In a mixing device and flow valve for wells, a flow tube, a hollow member adapted to be connected in the flow tube, a pipe section located within said member and spaced from the walls thereof to provide a mixing chamber having communication with the flow tube and an air chamber surrounding the mixing chamber, said air chamber having air inlet openings at its upper end for the passage of air under pressure, a rotatable member located within the mixing chamber in the path of liquid passing through the flow tube, means having communication with the 20 air chamber to direct air therefrom into the mixing chamber for mixture with the liquid to impart a swirling action thereto, and means located within the air chamber in the path of the air to operate the rotatable member.

25 2. In a mixing device and flow valve for wells, a flow tube, a hollow member adapted to be connected in the flow tube, a pipe section located within said member and spaced from the walls thereof to provide a mixing chamber having communication with the flow tube and an air chamber surrounding the mixing chamber, said air chamber having air inlet openings at its upper end for the 30 passage of air under pressure, a rotatable member located within the mixing chamber in the path of liquid passing through the flow tube, means having communication with the air chamber to direct air therefrom into the mixing chamber for mixture with the liquid to impart a swirling action thereto, air 35 driven propellers located within the air chamber in the path of air passing therethrough, and means operatively connecting the propellers and rotatable member to operate the latter.

40 In testimony whereof I affix my signature.
LEWIS E. BUNCH.
